UNITED STATES PATENT OFFICE.

WILLIAM W. STERLING, OF RUTH, NEVADA.

PLUG-VALVE.

1,274,345.

Specification of Letters Patent. Patented July 30, 1918.

Application filed January 19, 1918. Serial No. 212,724.

To all whom it may concern:

Be it known that I, WILLIAM W. STERLING, a native born citizen of the United States, residing at Ruth, in the county of 5 White Pine and State of Nevada, have invented new and useful Improvements in Plug-Valves, of which the following is a specification.

This invention relates to improvements 10 in valves and has especial relation to air valves used for controlling the supply of air upon either side of a piston and is intended for use in connection with air brake and other systems, although it is equally 15 well adapted for use in water systems.

The primary object of the invention is to provide a valve which is simple of construction, positive in operation and which will prevent creeping of the piston or loss of 20 air.

With the above objects in view the invention includes a casing for a plurality of diametrically disposed ports, which communicate with a central bore, in which there 25 is mounted for rotation a hollow plug, which is in turn provided with a diametrically arranged port and at each end of this port is provided with circumferentially arranged passages which communicate with and are 30 disposed upon each side of the said port, these passages being adapted to establish communication between the ports of the casing and a second hollow plug disposed within the first mentioned plug is also provided with a transversely arranged port 35 so as to establish communication through the diametrically arranged port of the first mentioned hollow plug, the second mentioned plug being held against movement 40 with respect to the casing and having therein a rotatably mounted plug which is provided with a transverse port adapted to register with the ports of the first and second mentioned hollow plugs.

45 In the drawings:

Figure 1 is a perspective view of a valve embodying the present invention;

Fig. 2 is a central longitudinal sectional view through the same;

50 Fig. 3 is a horizontal sectional view with the valve in neutral position;

Fig. 4 is a similar view showing the valve arranged to supply air to one side of a piston;

55 Fig. 5 is a view similar to Fig. 4 but the

valve is arranged to deliver air to the other side of the piston;

Fig. 6 is a detail perspective view of the outer plug; and

Fig. 7 is a similar view of the intermediate plug.

In the drawings, the valve casing which is shown at 10 is preferably cylindrical in form and is provided with diametrically disposed right angularly arranged ports, 65 which are indicated by the reference characters 11, 12, 13 and 14, the ports 11 and 13 being intake and exhaust ports. The casing 10 is provided with a concentric bore 15 and within this bore there is mounted 70 for rotation a hollow plug 16. The plug 16 is formed with a threaded extension 17 and a squared portion 18, the latter being adapted to receive the washer 19 and the former a nut 20, the latter acting to hold the plug 75 in position within the casing 10. The plug 16 is formed with a central bore 21 and with a diametrically disposed port 22, which communicates with the said bore. Also formed in the periphery of the plug are 80 radially arranged passages 23 and 24, the former being disposed upon opposite sides of one end of the port 22, while the latter is disposed upon opposite sides of the opposite end of the said port. The port 22 85 is adapted to establish communication between either of the sets of ports 11, 13 or 12, 14, while the passages 23 and 24 establish communication between any two of the adjacent ports, for example the ports 90 12 and 13 and the ports 11 and 14.

Seated within the bore of the plug 16 is a second hollow intermediate plug 25, the bore 95 26 of which communicates with a diametrically disposed port or passage 27. The plug 25 is provided with a threaded extension 28 and a squared portion 29, the former receiving a nut 30 which clamps a washer 31 against the bottom of the threaded extension 17 of the plug 16. The opposite end 100 of the plug 25 is provided with a squared portion 32, which enters a similarly shaped socket 33 provided with a yoke 34, the terminals of the latter being secured to the casing 10 upon diametrically opposite sides 105 thereof through the medium of screws 34. The plug 25 is fixed with respect to the casing 10, so that the position of the port 22 in the plug 16 may be changed with respect to the ports in the casing 10, without chang- 110

ing the relative position of the port 27, the plug 25 and the said casing. Mounted within the bore 26 of the plug 25, is an inner plug 35, which is provided with a port 36 which may be brought into register with the port 27 of the plug 25 to establish communication between the ports 12 and 14 of the casing through the medium of the port 22 in the plug 16 as shown in Fig. 3, or may 10 be turned at right angles to the port 27 so as to interrupt flow through the said port 27. The plug 35 is manually operated by a handle 37 positioned above the top of the plug 25. An operating handle 38 is also provided for the plug 16, this handle being in 15 the form of a wrench engaging the hexagonal extension 39 provided upon said plug.

When the parts are arranged in the position shown in Fig. 3, air will be equally distributed in the cylinder 40 upon either side of the piston 41, through the medium of pipes 42 and 43 communicating respectively with the cylinders and the ports 12 and 14. When the parts are in the position shown in Fig. 4 air will enter the port 13 of the casing 10 and will travel through the passage 23, the port 12 and the pipe 42 into the cylinder 40 upon one side of the piston 41, the air exhausting upon the opposite side of the piston through the pipe 43, the port 14, the passage 24 and the exhaust port 11. Fig. 5 illustrates the parts in position to supply air through the pipe 43 to the side 35 of the cylinder opposite that supplied in Fig. 4 and to exhaust the air from the other side of the piston. As the plug 25 remains fixed with respect to the casing 10, a rotary movement of the plug 16 will cause the plug 40 25 to interrupt the port or passage 22 as shown in Figs. 4 and 5 and to further provide against seepage or loss through the port 27, the plug 35 may be rotated to interrupt the port or passage 27. By this 45 means loss of air through the valve is absolutely prevented and creeping of the piston eliminated.

Having described the invention, what is claimed is:—

50 1. A valve embodying a casing provided with a plurality of diametrically disposed ports communicating with a central bore, a

hollow plug rotatably mounted within said central bore, a diametrically arranged port within the hollow plug, circumferentially arranged passages formed in the hollow plug, said passages communicating with and disposed upon each side of each end of the diametrically arranged port, said passages being adapted to establish communication between certain of the ports of the casing, a plug disposed within the hollow plug and having a transverse port to register with the transverse port of the hollow plug and means for holding the second mentioned plug against movement with respect to the casing.

2. A valve embodying a casing provided with a plurality of diametrically disposed ports communicating with a central bore, a 70 hollow plug rotatably mounted within the said bore, a diametrically arranged port within the hollow plug, circumferentially arranged passages formed in the hollow plug, said passages communicating with and disposed upon each side of each end of the diametrically arranged port and being adapted to establish communication between certain of the ports of the casing, a second hollow plug disposed within the first mentioned plug and having a transverse port therein to establish communication with the diametrically arranged port of the first mentioned plug, means for holding the second mentioned plug against movement with respect to the casing and a plug rotatably mounted within the second mentioned plug for interrupting and establishing communication centrally through the second mentioned plug.

3. A valve embodying a casing provided with a plurality of diametrically and right angularly disposed ports communicating with a central bore, a plurality of concentrically arranged plugs mounted within said casing, each of said plugs being provided with a transverse port adapted to be brought into registry with each other to provide a continuous passage transversely of the plugs and circumferential passages formed in the outermost plug, whereby communication may be established between the ports.

In testimony whereof I affix my signature.

WILLIAM W. STERLING.
